United States Patent Office

Des. 180,348
Patented May 21, 1957

180,348

LETTER OPENER OR THE LIKE

Cecil B. Woofter, Minneapolis, Minn., assignor to U. O. Colson Company, Paris, Ill., a corporation of Delaware

Application May 17, 1956, Serial No. 41,527

Term of patent 7 years

(Cl. D74—1)

Fig. 1 is a top plan view of a letter opener or the like, showing my new design;

Fig. 2 is an edge elevational view thereof;

Fig. 3 is a bottom plan view thereof;

Fig. 4 is an end elevational view looking at the left hand end of Fig. 2; and

Fig. 5 is an end elevational view looking at the right hand end of Fig. 2.

The dominant features of the design are shown in full lines.

I claim:

The ornamental design for a letter opener or the like, as shown and described.
